DESIGN FOR A COVERED EYELET BUTTON

William Novick, Brooklyn, N. Y.

Application September 11, 1943, Serial No. 111,108

Term of patent 14 years

(Cl. D17—2)

To all whom it may concern:

Be it known that I, William Novick, a citizen of the United States residing at the Borough of Brooklyn, in the county of Kings and State of New York, have invented a new, original, and ornamental Design for a Covered Eyelet Button, of which the following is a specification, reference being had to the accompanying drawing, forming a part thereof.

Fig. 1 is a top view of a covered eyelet button showing my new design; Fig. 2 is a sectional view on the line 2—2 of Fig. 1, and Fig. 3 is a perspective view of the outer frame of the button.

The body portion of the button comprises the bottom wall with the circular wall at right angles thereto. The outer frame of the button comprises the cylindrical wall, the bottom wall and the annular top wall with gripping teeth. The cloth for the button is cemented to the bottom wall of the said body portion.

I claim:

The ornamental design for a covered eyelet button, as shown and described.

WILLIAM NOVICK.
